UNITED STATES PATENT OFFICE.

EWALD VANDERSTEIN, OF DULKEN, GERMANY.

FURNACE WITH BLAST HEATER.

Application filed January 21, 1925, Serial No. 3,724, and in Belgium October 29, 1924.

This invention has reference to furnaces, particularly cupola furnaces provided with blast heating means, i. e., recuperators or regenerators, and it is one of the important objects of this invention to so arrange the said blast heating means and the communicating passages connected therewith, as to shorten the paths of the gases and of the blast, and so that the blast chambers and passages may be arranged about a pair of furnaces so as to constitute therewith a compact working unit.

The invention will be further described with reference to the accompanying drawings, showing by way of example some embodiments of the principles of this invention, Figure 1 being a front elevation with parts in section on the line 1—1 Figure 3, and Figure 2 is a corresponding side view. Figure 3 is a corresponding plan view partly in horizontal section. In Figures 4 and 5 a modified arrangement is shown in front elevation with parts in section and respectively in plan view.

In the form of the invention according to Figures 1 to 3 a double blast heater 1, 2 comprising a pair of regenerators is disposed at the rear of the furnaces 3 and 4, and these regenerators communicate respectively with blast preheating chambers 1^a, 2^a which are heated therefrom and are directly connected by short conduits 5, 6, 7, 8 to the retorts or torch chambers or flues 9, 10, 11, 12 of the furnaces. A and A', respectively, are the air inlet and waste gas exhaust pipes communicating with the regenerators 1, 2, and B is the usual reversing valve adjustable for reversing the flow of the air and gases. In the position of the valve B shown in Figure 3, fresh air enters through the pipe A into the regenerator 2, and flows through the chambers 1^a, 2^a at the opposite sides thereof and the conduits 5, 8 into the retorts 9, 12 of furnaces 3, 4, across the furnace chambers, into the retorts 10, 11, and through conduits 6, 7 to the regenerator 1, from which the waste gases discharge through the pipe A'. When the damper B is reversed, the fresh air entering through pipe A enters regenerator 1, and flows through the conduits 6, 7, and retorts 10, 11, and across the furnaces 3, 4 in the reverse direction from that above-described, and then back through retorts 9, 12, conduits 5, 8 and chambers 1^a, 2^a to the second regenerator 2, and then out through the

pipe A'. By this arrangement a very advantageous connection of the different parts of the plant is produced without the necessity of any complicated and extended and 60 subterraneous passages. The arrangement of the nozzles or twyers in the furnace heads remains otherwise unchanged; and the efficiency and mode of operation is not affected in spite of the novel means of conducting the 65 gases and air.

In the modified arrangement according to Figures 4 and 5 of the drawing there is the difference that the double blast heater comprising the regenerator 13, 14 is arranged 70 intermediate of the furnaces 15, 16, the conductors 17, 18, 19, 20 leading to and from the retorts or torch chambers or flues 21, 22, 23, 24 of the furnaces being connected with blast reheating chambers 13^a, 13^b, 14^a, 14^b 75 communicating with and heated from the regenerators. As a result of the described arrangement of the blast preheating chambers 13^a, 13^b, 14^a, 14^b the particles of dust carried over by the waste gases are almost 80 completely deposited in these preliminary chambers, so that the waste gases will enter the blast heaters 13^a, 13^b, 14^a, 14^b in a purified condition. In this form of the invention the corresponding retort chambers of the furnaces 21, 22, 23, 24 are connected to each other by a by-pass conduit 25 and respectively 26 85 in such a manner that a portion of the fresh blast is conducted to the delivery side of the furnace where it will cause the substantially 90 complete combustion of the carbon monoxide carried by the exhaust gases. This admission of the fresh blast may also be effected directly from the blast conduit. Whenever required, the plurality of blast heating 95 chambers which constitute a unit, may be arranged around one of the furnaces. With the arrangement of the valve B shown in Figure 5, air enters through pipe A to regenerator 13, and through chambers 13^a, 13^b, and conduits 17, 18, to retorts 21, 22, and across the furnaces 15, 16, in one direction, thence into retorts 23, 24, and through conduits 19, 20, chambers 14^a and 14^b to regenerator 14, and thence through exhaust pipe 100 A'. Upon reversal of the valve B, the direction of flow of the air and gases will be reversed in an obvious manner.

The invention has been shown and described in its broad aspects only, and it will be understood that it may be varied to meet the various requirements of use, and without

deviating from the spirit of the invention, as set forth in the claims hereunto appended.

I claim:—

1. The combination of a pair of blast furnaces, retort chambers at opposite sides of each furnace, a pair of regenerators arranged side by side, preheaters arranged at opposite sides of the regenerators, each preheater being in direct communication with a regenerator and the retort chambers of one of the furnaces, a valve casing, pipes connecting said casing at two of its sides with the regenerators, air supply and waste gas exhaust pipes communicating with the casing at diametrically opposite sides thereof and at right angles to the pipes first-named, and a reversing valve in said casing for connecting the air supply pipe with one of the first-named pipes and the waste gas exhaust pipe with the other first-named pipe, or vice versa.
2. The combination of a pair of blast furnaces arranged in transverse alinement, retort chambers at opposite sides of each furnace, a pair of regenerators arranged side by side and in rear of the furnaces, preheaters at the opposite sides of the regenerators, each preheater being in direct communication with a regenerator and the retort chambers of one of the furnaces, a valve casing disposed above the regenerators, pipes connecting said casing at two of its sides with the regenerators, air supply and waste gas exhaust pipes communicating with the casing at diametrically opposite sides thereof and at right angles to the pipes first-named, and a reversing valve in said casing for connecting the air pipe with one of the first-named pipes and the waste gas exhaust pipe with the other first-named pipe, or vice versa.

necting said casing at two of its sides with the regenerators, air supply and waste gas exhaust pipes communicating with the casing at diametrically opposite sides thereof and at right angles to the pipes first-named, and a reversing valve in said casing for connecting the air supply pipe with one of the first-named pipes and the waste gas exhaust pipe with the other first-named pipe, or vice versa.

3. The combination of a pair of blast furnaces arranged in transverse alinement, retort chambers at opposite sides of each furnace, a pair of regenerators arranged side by side, preheaters at opposite sides of the regenerators, each preheater being in direct communication with a regenerator and the retort chambers of one of the furnaces, a valve casing disposed above the regenerators, pipes connecting said casing at two of its sides with the regenerators, air supply and waste gas exhaust pipes communicating with the casing at diametrically opposite sides thereof and at right angles to the pipes first-named, and a reversing valve in said casing for connecting the air pipe with one of the first-named pipes and the waste gas exhaust pipe with the other first-named pipe, or vice versa.

EWALD VANDERSTEIN.
